JOHN M. ROHLFING, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

SIDE BEARING WITH CONTACT-SHOE.

1,244,782.

Specification of Letters Patent. Patented Oct. 30, 1917.

Application filed March 29, 1917. Serial No. 158,277.

To all whom it may concern:

Be it known that I, JOHN M. ROHLFING, residing at St. Louis, Missouri, and being a citizen of the United States, have invented 5 certain new and useful Improvements in Side Bearings with Contact-Shoes, of which the following is a full, clear, and exact description, such as will enable others skilled in the art to which it appertains to make 10 and to use the same, reference being had to the accompanying drawings, which illustrate the preferred form of the invention, though it is to be understood that the invention is not limited to the exact details of 15 construction shown and described, as it is obvious that various modifications thereof within the scope of the claims will occur to persons skilled in the art.

In said drawings:

20 Figure 1 is a view of my improved side bearing partially in plan, and partially in horizontal section to show the relation of some of the internal members;

Fig. 2 is a transverse section taken on 25 the line 2—2 of Fig. 1; and

Fig. 3 is a longitudinal vertical section taken on the line 3—3 of Fig. 1.

This invention relates to anti-friction 30 bearings applicable to the bolsters of rail-way cars to act as side bearings. A suitable casing or housing is provided, which is adapted to be attached to a bolster at a proper location, such casing being provided with separate runways, there being rollers 35 adapted to bear on and traverse either runway.

It is a purpose to interconnect a shoe, adapted to be engaged and actuated by another and co-operating bolster, with the 40 rollers so that the shoe will be normally suspended from such rollers, and will be self-centering thereon.

A further aim is to arrange the shoe so that, under the action of the bolster which 45 is adapted to engage and actuate it, the shoe will cause the rollers to be supported by it and further caused to roll on the runway opposed to that on which the rollers normally bear. The shoes, rollers and last mentioned runway are then to contact with each other and be in compression, the parts under 50 this stress being adequately rugged to easily withstand it.

The shoe and runways are in anti-frictional engagement with the rollers, irrespec-

tive of which runway the rollers travel on, and a further feature lies in the ability of the shoe to provide a bearing at points beyond the bolster. The shoe may thus extend its effective engagements with the bolster actuating it beyond the possible travel of the rollers, and beyond the extent of such side bearings as have self-contained rollers. 60

Other features manifesting themselves hereinafter, of course, come within the scope 65 of the present invention.

Referring to the drawing, 1 indicates a body bolster of a railway car and 2 the truck bolster or the upper surface of a side bearing carried thereby, both being indicated by dot and dash lines. Positioned on the under side of body bolster 1 is a casing or housing 3 comprising side walls 4 and an overhead wall 5. Projecting from the upper portions of side walls 4 are lugs or 70 flanges 6 through which fastening means are adapted to pass to secure the casing 3 to the body bolster 1. Projecting inwardly from each side wall 4 of casing 3 is a bottom flange 7, said flanges constituting a 75 lower track. The terminals of flanges 7 are upturned, as indicated at 10 in dotted lines in Fig. 3, to form stops, hereinafter referred to. Positioned above and extending over each flange 7 is a wearing strip 8 secured 80 by rivets or other suitable means to portions 9 of the overhead wall 5 that are adjacent the side walls 4. Preferably portions 9 are laterally spaced apart, though in some constructions it may be feasible to combine 85 90 them as a single plate.

Extending substantially from side wall to side wall and having ends projecting between the track-forming flanges 7 and the upper wearing strips 8, which strips form 95 another track or runway, are a plurality of rollers 11. Rollers 11 also extend through slots 12 in the upper portion of a shoe 13, said slots being, if desired, conveniently formed by making the upper portion of shoe 100 13 in the form of loops 14. The upper sides of loops 14 may be anticlinal and rest upon the upper sides of rollers 11, whereby shoe 13 will be self-centering when not engaged by the truck bolster. It will thus be seen 105 that when the rollers 11 are resting on the track formed by flanges 7, shoe 13 will be suspended from said rollers.

In assembling, rollers 11 are passed 110 through the loops 14 of shoe 13 and with

that shoe are inserted through one of the open ends of the casing. Said casing is in general of channel-shaped form having both of its ends open and after the insertion of 5 rollers 11 and shoe 13, said rollers 11 will normally rest upon the track flanges 7. Thereafter, wearing strips 8 may be inserted and secured as previously indicated, whereupon the terminals of wearing strips 8 will 10 be so juxtaposed to the upturned curved stops 10 at the ends of flanges 7 that rollers 11 cannot escape from casing 3 and consequently shoe 13 is also retained in place.

When the side bearing is installed on the 15 body bolster 1 and the car is in service, whenever the car body tilts, as in response to rounding a curve, body bolster 1 and truck bolster 2 will relatively approach each other on one side of the car. When this happens, 20 truck bolster 2, or the side bearing mounted thereon, will engage the under side of shoe 13 forcing it upwardly between laterally extending spaced wearing strips 8, but not sufficiently for it to encounter the overhead 25 wall 5.

In moving upwardly, the lower or engagement portion of shoe 13 will encounter the rollers 11 raising them so as to cause them to bear upon the under sides of wearing strips 30 8, along which they are then adapted to be rolled by the shoe 13 under the influence of truck bolster 2.

Under this condition, the lower thick portion of shoe 13, the solid rollers 11, which 35 may be tubular if desired, and the wearing strips 8 are in a state of compression.

During the continued relative swiveling of the body and truck bolsters, and at such time as the truck bolster has actuated the 40 shoe 13 to raise rollers 11 into contact with wearing strips 8, the rollers and shoe 13 will move transversely of body bolster 1. There will be a relative opposite rolling of the under surfaces of wearing strips 8 and the 45 shoe 13 on the rollers 11 when said rollers and shoe are traveling as indicated, and after a certain amount of travel in one direction, one of the rollers will engage the terminal stops 10 at one end of flanges 7. The 50 roller so arrested will also be engaged by the inner wall of loop 14, which engagement causes the shoe to be held in fixed relation to the casing in a position in which the shoe protrudes from the end of the casing, thereby forming a further track for the truck bearing to engage as the truck continues to swivel. This action is adapted to take place at either end of casing 3.

After the car has rounded the curve that 60 produced the opposite swiveling of the body and truck bolsters, said bolsters will again become vertically aligned and shoe 13 and rollers 11 will have been caused to resume their normal positions, as indicated in Fig. 65 3. In so resuming these normal positions,

the rollers again become rideable on the lower track formed by flanges 7, and, due to the anticinal upper portions of the loops 14, the shoe 13 will automatically center itself on the rollers 11 by gravity. 70

The side bearing is then ready for a repetition of the just described actions, responding to the influence of truck bolster 2 in whichever direction it swivels.

The side bearing herein disclosed is composed of very few parts which are simple and economical to produce and constitutes a highly efficient side bearing quite unlikely to get out of order. If at any time the rollers should accidentally become jammed 80 between the side walls 4 of casing 3, this will not result in the inoperativeness of the device as shoe 13 will reciprocate as before. 85

What I claim is:

1. In combination in a side bearing, a casing adapted for attachment to a bolster, a shoe movable longitudinally thereof and anti-friction rollers passing through the latter without interfering with the movement thereof. 90

2. In combination in a side bearing, a casing provided with a track, a shoe projecting below the track and movable in said casing, rollers from which said shoe is suspended rideable on said track, and means limiting the travel of said rollers, the rollers being adapted to limit the travel of said shoe. 95

3. In combination in a side bearing, a casing provided with upper and lower runways, rollers normally bearing on the lower runway and a shoe hung from said rollers and adapted under applied force to cause said rollers to bear on and traverse the upper runway and to afford a roller bearing for said shoe. 100

4. In combination in a side bearing, a casing having spaced bearing surfaces, a roller and a reciprocatory shoe, said roller being adapted to bear on one of said surfaces to hold the shoe suspended and also to be held by said shoe in rolling contact with the shoe and another of said surfaces. 105

5. In combination in a side bearing, a casing having spaced bearing surfaces, rollers and a shoe, said rollers being adapted to ride on one of said surfaces and hold said shoe suspended and to be held by said shoe to ride on another of said surfaces and to automatically resume the shoe-suspending relation with the first-mentioned surface. 115

6. In combination in a side bearing, a casing having spaced bearing surfaces, rollers and a shoe, said rollers being adapted to ride on one of said surfaces and hold said shoe suspended and to be held by said shoe to ride on another of said surfaces and to automatically resume the shoe-suspending relation with the first-mentioned surface, said shoe being formed to automatically center itself on said rollers. 120

130

7. In combination in a side bearing, a casing and a shoe each having upper and lower bearing surfaces, and rollers extending between the bearing surfaces of both and in contact with the lower and upper bearing surfaces of said casing and shoe, respectively, to maintain said shoe in a predetermined position, and in contact with the upper and lower bearing surfaces of said casing and shoe, respectively, for a relatively opposite rolling of the casing and shoe.

8. In combination in a side bearing, a casing having spaced runways, a shoe provided with a looped portion extending into said casing and a roller normally bearing on one of said runways and extending through the looped portion of said shoe to normally hold said shoe suspended, said shoe being adapted under applied force and together with the roller and another of said runways to be placed in compression and to have anti-frictional reciprocation on said roller.

9. In combination in a side bearing, a casing having parallel walls each provided with a flange, spaced wearing strips overlying said flanges, rollers spanning and normally ridable on said flanges, and a shoe having looped portions through which said rollers pass and adapted to cause said rollers to roll on said wearing strips and form anti-friction bearings for said shoe.

10. In combination in a side bearing, a casing having spaced track-forming members, stops, wearing-strips vertically spaced from said track members, a shoe extending between said track members, and rollers passing through said shoe and bearing on said track members, said shoe being adapted to cause the rollers to bear on and traverse said wearing strips, to become arrested by said stops and also to travel in anti-frictional engagement with said rollers and subsequently to become arrested by the latter.

11. In combination in a side bearing, a casing provided with spaced lower track-forming members, spaced wearing strips mounted thereabove, a shoe intermediate

said track members, and rollers passing through slots in said shoe and bearing on said track members, said shoe being adapted to pass between said wearing strips and cause said rollers to travel on said strips and to in turn travel on said rollers.

12. In combination in a side bearing, a casing having track members provided with terminal stops, separately formed wearing members vertically spaced therefrom, secured to said casing and having terminals adjacent said stops, a slotted shoe and rollers passing therethrough adapted to ride on either said track members or wearing strips and also adapted to be inserted or removed only when there is a relative altering of the relation between the strip terminals and said stops.

13. In combination in a side bearing, a casing, vertically spaced runways therein, rollers ridable on either runway, stops for said rollers and a shoe supported by said rollers when the latter are on one runway and adapted to support the rollers in engagement with the other runway.

14. In combination in a side bearing, a casing, vertically spaced runways therein, rollers ridable on either runway, stops for said rollers and a shoe supported by said rollers when the latter are on one runway and adapted to support the rollers in engagement with the other runway, the rollers being adapted to return to the first runway and said shoe be self-centering on said rollers thereafter.

15. In combination in a side bearing, a casing, vertically spaced runways therein, rollers ridable on either runway, stops for said rollers and a shoe supported by said rollers when the latter are on one runway and adapted to support the rollers in engagement with the other runway, said shoe being adapted to continue traveling so as to pass partly out of said casing.

In witness whereof I have hereunto set my hand.

JOHN M. ROHLFING.
